UNITED STATES PATENT OFFICE.

KARL KIEFER, OF CINCINNATI, OHIO.

DESIGN FOR A BOTTLE.

SPECIFICATION forming part of Design No. 32,307, dated March 6, 1900.

Application filed January 5, 1899. Serial No. 701,298. Term of patent 7 years.

To all whom it may concern:

Be it known that I, KARL KIEFER, a citizen of the United States, and a resident of Cincinnati, in the county of Hamilton and State of Ohio, have invented a new and original Design for Bottles, of which the following is a specification, reference being made to the accompanying drawings.

Figure 1 is a perspective view of my design.
10 Fig. 2 is a horizontal cross-section of the bottle.

The leading feature of my design consists in a horseshoe forming the outlines of two sides of a bottle. The bottle itself is of the 15 shape as shown in the drawings and commonly known as a "flask." The two flat faces

are outlined by a horseshoe shape. The horseshoe itself is represented in relief, nails and grooves being shown. Space A, which is contained within the horseshoe design on both 20 sides of the bottle, affords opportunity for lettering or a label.

Having described my invention, what I claim, and desire to secure by Letters Patent, is—

25 The design for a bottle herein shown and described.

KARL KIEFER.
